(57) **CLAIM**

The ornamental design for a deer feeder hopper, as shown and described.

DESCRIPTION

FIG. 1 is a front perspective view of the deer feeder hopper, showing my new design;

FIG. 2 is a front view thereof;

FIG. 3 is a rear view thereof;

FIG. 4 is right side view thereof;

FIG. 5 is a left side view thereof;

FIG. 6 is a top plan view thereof; and,

FIG. 7 is a bottom view thereof.

The broken lines in the drawings are for the purpose of illustrating unclaimed portions of the deer feeder hopper and form no part of the claimed design.

1 Claim, 4 Drawing Sheets
